PAPER ROLL FINISHING APPARATUS
Paul M. Henson, Lynn Haven, Fla., and Joe Spivey, Jr.,
Pine Bluff, Ark., assignors to International Paper Company,
New York, N.Y., a corporation of New York
Filed July 6, 1962, Ser. No. 207,908
20 Claims. (Cl. 156—361)

This invention relates to paper roll finishing. More particularly, it relates to an apparatus made up of several sub-assemblies which cooperate to accomplish the objects of gluing the loose tail of a paper roll to the body thereof and plugging the ends of the hollow cores about which the paper roll is wound for purposes of storage and shipment.

Broadly, the present invention encompasses an electro-mechanical unit having rotatable roller means for positioning an unfinished paper roll initially with reference to a gluing sub-assembly which effects the application of paste or glue on the roll or on the inside surface of the tail end of the wound paper web and then with reference to two reciprocatingly movable core plugging sub-assemblies which effect the insertion of plugs made of wood, metal, or plastic into both ends of the hollow core forming the axle of the paper roll to give such core added strength and to provide a means of purchase on such roll. In addition, the rotatable roller means are adapted to effect the pressing of the paper web tail against the body of the rolled paper web when glued and the core plugging sub-assemblies are adapted to select pairs of plugs from random assortments thereof and, by means of a built-in capacity for self-adjustment, to position such pairs axially of the hollow core. Further, the unit can include means for facilitating and regulating its paper roll intake and discharge.

For a better understanding of the present invention, reference should be had to the attached drawings in which:

FIGURE 1 shows a plan view of the equipment in accordance with the present invention;

FIGURE 2 shows a schematic view of the equipment of FIGURE 1;

FIGURE 3 shows a side view of the equipment of FIGURE 1;

FIGURE 4 shows an isometric view of the equipment of FIGURE 1;

FIGURE 5 shows another schematic view of the equipment of FIGURE 1;

FIGURE 6 shows another isometric view of the equipment of FIGURE 1;

FIGURE 7 shows a cross-sectional view of the equipment of FIGURE 1, taken along line 7—7;

FIGURE 8 shows a plan view of the equipment of FIGURE 7, taken along line 8—8;

FIGURE 9 shows a fragmentary side view of the equipment of FIGURE 1;

FIGURE 10 shows an exploded isometric view of a portion of the equipment of FIGURE 1;

FIGURE 11 shows a end view of a portion of the equipment of FIGURE 1; and,

FIGURES 12, 13 and 14, 15, and 16 show circuit diagrams in accordance with the present invention.

FIGURE 1 depicts the equipment of the present invention from above, including horizontally disposed rollers 10 and 11. FIGURE 2 illustrates the positioning of paper rolls with respect to such equipment. Thus, roll A is poised on inclined plane or ramp 13 where it is held back by a chock 14 which is connected to and movable with piston 15 when urged by fluid pressures in cylinder 16. Solenoid 17 dictates such pressures. Again, roll B is positioned on rollers 10 and 11 at about floor level, having been halted in its progress out of the situation of

2

roll A down ramp 13—which progress began with the withdrawal of chock 14 from a point where roll B impinged against it—by chock 18 connected through rod 19 with fluid cylinder 20 and solenoid 21 therefor. Conveniently, such positioning takes place when roll C (having been finished in accordance with the present invention, kicked off rollers 10 and 11 by prod roller 22 on forked roller-bearing piston 23 in fluid cylinder 24 operated by solenoid 25 at about the time chock 18 and rod 19 disposed therein are retracted, and rolled by gravity farther down ramp 13 and into trough 26) leaves a gap across which light beam 27 can travel freely (as it could not when roll C lay in such gap) from its source 27a to a detecting means 27b therefor to signal for the forwarding of the next unfinished roll down ramp 13 to rollers 10 and 11. Similarly, it is convenient and preferable to have the action of prod roller 22 on the roll resting on rollers 10 and 11 timed to follow the finishing of such roll in accordance with the invention.

Parts of the gluing sub-assembly and phases of their operation are shown in FIGURES 1, 3, 5, and 7. Unfinished roll A, having descended down ramp 13 to rollers 10 and 11, is caused to rotate slowly thereon in clockwise fashion, as viewed in FIGURE 5, in response to a predetermined signal to the drive means 28, e.g., motor, connected to the rollers. Means D and E providing air jets lift the tail F of roll A as it rotates slowly, so as to cause such tail to fall substantially flatly against the down-roller end of ramp 13. When tail F so falls, it interrupts light beam 29, emanating, for example, from light source means 29a and impinging on light detecting means 29b, until the continued slow rotation of roll A draws tail F from between 29a and 29b and beam 29 passes between them unimpeded. Once such interruption ends, rollers 10 and 11 are caused to stop the rotation of roll A by means of a signal transmitted to roller drive means 28 from detecting means 29b.

At this juncture, gluing heads 30 mounted on horizontally disposed pistons 31a in pneumatic cylinders 31, which are, in turn, mounted upon the divergently and convergently movable core plugging sub-assemblies, should be considered. Pistons 31a are adapted to move, in response to a predetermined signal, along their axes and relatively to such sub-assemblies and to carry gluing heads 30 toward or away from each other. The set of the heads 30 is preferably such that the sprays emanating from them, when the cylinders approach one another, for example, above the upper surface of tail F or roll A, cross to give the most efficient gluing pattern thereon. To prevent rotation of heads 30 and pistons 31a within cylinders 31 and the loss of their setting, pilots 32 are fastened at their upper ends to the pistons or heads and slidably engaged at their lower ends in channel 33 (FIGURE 7). Cylinders 31 do not, however, feed gluing heads 30; this is done by means of glue hoses 34 which are in a fluid connection with heads 30.

Gluing heads 30 and pilots 32 are also so positioned in relation to one another that, preferably, at least one of them can by means of feeler 35 actuate a switch 36 when the gap between them decreases to a certain predetermined minimum length. The actuation of switch 36 results both in the ending of the strokes of pistons 31a toward one another and in the ending of the glue flow from heads 30 mounted on such pistons. Preferably, it also results in the mutual retraction of pistons 31a and in the re-energizing of drive means 23 for the purpose of rotating roll A on rollers 10 and 11 to permit the drawing-up of tail F between the body of roll A and the upper surfaces of rollers 10 and 11 and the affixing of glued tail F to such body with the aid of the weight thereof.

Where the core plugging sub-assemblies do not participate in the roll tail gluing operation, they cooperate therewith. Such sub-assemblies include plug hoppers 40 which are depicted in FIGURES 1, 3, 4, 6, 10, and 11. These plug hoppers include truncated hollow core barrels 40a, into the open narrow end of which the plugs 40b, which can be hollow, are initially dumped at random. Barrels 40a are rotated about their laterally disposed longitudinal axes by drive means 40c as soon as the equipment is initially turned on or even before the gluing operation begins and plugs 40b are thereby caused to move down the sloping interiors of barrels 40a toward barrel backing plates 40d and into plug orienting apertures 40e formed by means of and between barrels 40a and plates 40d. A complete movement of plugs 40b into apertures 40e is, preferably, made to depend upon a juxtapositioning of plugs 40b such that their profiles generally and perhaps somewhat loosely conform to the predetermined configurations or outlines of the apertures.

Funnel members 40f are a part of plug hoppers 40 and of the core plugging sub-assemblies of the present invention and they are provided to keep plugs 40b, once oriented for further use by means of apertures 40e, from falling through such apertures, from becoming disoriented, and in a systematic flow to the rest of the core plugging sub-assemblies. Such funnel members are themselves adapted to serve several functions. By means of the downwardly depending throats or necks 40g of such members, the oriented plugs 40b leave apertures 40e of barrels 40a when the revolving barrels and apertures bring them into registry with mouths 40h at the upper ends of necks 40g and are directed toward plug pick-up stations 40j at the lower ends of necks 40g. By means of cheek pockets 40i of such funnel members, a few overflow plugs 40b which cannot find space in necks 40g are kept temporarily stored and oriented until plug removals at stations 40j permit them to enter into necks 40g. Larger overflows are, of course, returned to barrels 40a from pockets 40i for further agitation and eventual reorientation.

With the disposition of a pair of oriented plugs at pick-up stations 40j, it is timely to consider the elements of the core plugging sub-assemblies of the present invention other than plug hoppers 40. Most of such elements are combined to provide two devices which cooperate to effect the same principal purpose, i.e., the plug of the hollow paper roll cores, but which are capable of a certain degree of independent action or adjustment in achieving such results. These devices include reciprocating trolley carriage members 50 and 70 movably mounted on pairs of horizontally positioned trolley lead screws 51 and 71, respectively, by means of pairs of trolley sleeve nuts 52 and 72, respectively. Lead screws 51 and 71, which lie parallel to rollers 10 and 11, but preferably below floor level, are connected for rotation to respective reversible drive means 53 and 73, which are disposed beneath such screws. When rotated by such drive means, lead screws 51 and 71 can carry trolley carriage members 50 and 70 away from each other, at least until some portions of such members impinge against shut-off switch means 54 and 74 connected to such drive means. Shut-off switch means 54 and 74 are positioned to provide the shut-off at such times as trolley carriage members 50 and 70 are suitably disposed before oriented plug pick-up stations 40j.

As shown in FIGURES 4, 8, and 9, fluid cylinders 55 and 75, which are mounted horizontally on elevator plates 50a and 70a in trolley carriage members 50 and 70 by means of clevises 55a and 75a, hold ends of pistons 56 and 76, the other ends of which are pivotally attached through horizontally rotatable lever arms 57 and 77 to vertically disposed rotatable shafts 58 and 78. As also shown, frames 59 and 79 are affixed on their end plates 59a and 79a to shafts 58 and 78 and fluid cylinders 60

and 80 are disposed within frames 59 and 79. It will be noted that frames 59 and 79 and cylinders 60 and 80 lie between horizontally positioned and substantially triangular, spaced pairs of elevator plates 50a and 50b and 70a and 70b within trolley carriage members 50 and 70 and that such elevator plates form, together with elevator spacer sleeve nuts 61 and 81 mounted on vertically disposed, rotatable elevator lead screws 62 and 82, elevator carriage members 63 and 83. Elevator plates 50a and 50b and 70a and 70b are maintained in a parallel relation by nuts 61 and 81 to the ends of which such plates are affixed by welding or the like.

When pistons 56 and 76 are ejected, in response to a predetermined signal, from cylinders 55 and 75, they cause, with the aid of the noted linkage, cylinders 60 and 80 to revolve approximately 90° from positions within elevator carriage members 63 and 83 and paralleling rollers 10 and 11 to positions substantially without members 63 and 83 and axially or oriented plugs 40b in pick-up stations 40j. And, when 60a and 80a are ejected, in response to another predetermined signal, from cylinders 60 and 80, their outer ends—which can be adapted to impale or grasp the plugs, preferably loosely—pick up the plugs. Thereafter, spindles 60a and 80a and pistons 56 and 76 are or can be retracted into their respective cylinders, cylinders 60 and 80 are or can be returned to positions parallel to rollers 10 and 11 as shown in FIGURES 3, 6, and 7, and trolley carriage members 50 and 70 are or can be traveled toward one another and toward paper roll A on rollers 10 and 11 by the actuation of lead screws 51 and 71 and their drive means 53 and 73.

Trolley carriage members 50 and 70 are not required to arrive simultaneously at the ends of roll A. Such a simultaneous arrival can, as a matter of fact, occur only if and when roll A is initially positioned with a degree of accuracy which takes into minute account the speed and distances members 50 and 70 travel. But, when they do arrive, as shown in FIGURES 1, 3, 6, and 7, electrical switch means 64 and 84 mounted on the forward ends of members 50 and 70 are brought into play in like fashion; namely, such switch means, having made contact with a roll end, stop the forward progress of the trolley carriage member to which they are affixed. Then, when both switches 64 and 84 have stopped the flow of energy to drive means 53 and 73 of lead screws 51 and 71 and the forward progress of trolley carriage members 50 and 70 as shown in FIGURE 9, energy is caused to flow to drive means 65 and 85 for lead screws 62 and 82 on which elevator carriage members 63 and 83 are mounted. Drive means 65 and 85 and lead screws 62 and 82 are respectively connected by means of standard worm and bevel gear arrangements 66 and 86. With the energizing of drive means 65 and 85, lead screws 62 and 82 turn and, at, preferably the same rate of speed, cause elevator carriage members 63 and 83 to rise within stopped trolley carriage members 50 and 70.

As shown in FIGURES 7 and 9, a light source means 67a is mounted on elevator plate 50a in the vertical plane of spindle 60a and plug 40g impaled thereon. By design, such vertical plane bisects the horizontal distance between the centerlines of rollers 10 and 11. Further, light source means 67a is directed to cast a beam of light 67 in a horizontal line substantially parallel to rollers 10 and 11 and to hollow core G of roll A as it nestles on and between rollers 10 and 11. By this orientation, beam 67 is adapted to travel through core G and impinge upon a light detecting means 67b—which is mounted on elevator plate 70a in a position and with a setting comparable to that of light source means 67a on elevator plates 50a—as soon as the rise of elevator carriage members 63 and 83 within stopped trolley carriage members 50 and 70 brings means 67a and 67b to or near the lowermost edges of the open ends of core G.

The moment beam 67 is sighted by detecting means 67b, a timer means is actuated thereby and it regulates

the further upward movement of elevator carriage members 63 and 83 to the extent that they will rise no further than the vertical distance between the axial lines of beam 67 and spindles 60a and 80a and to the extent that they will locate plugs 40b impaled on such spindles axially of hollow core G.

Plugs 40b are inserted into the ends of core G by means of the extension of spindles 60a and 80a out of cylinders 60 and 80 in response to a predetermined signal which is, preferably, initiated by the timer means. Plugs 40b are then driven home in the ends of core G with the help of flanged collars 60b and 80b on and affixed to spindles 60a and 80a, respectively.

It is upon the withdrawal of spindles 60a and 80a from core-inserted plugs 40b that, preferably, the roll tail gluing operation enters the gluing head retraction phase. Or, in other words, the preferred sequence comprehended by the operation of the present gluing sub-assembly and core plugging sub-assemblies sees tail F of roll A blown to lie flat down ramp 13 not later than the pick-up of oriented plugs 40b at stations 40j and sees tail F glued when trolley carriage members 50 and 70 have brought impaled plugs 40b to the ends of roll A. This will be better understood from a review of the circuitry for the present equipment shown in FIGURES 12 to 16.

Assuming that the machine of the present invention is empty and that the roll to be finished (roll A) is still on ramp 13 held by chock 14, the preferred mode of operation and the means of effecting it are as follows:

Referring first to FIGURE 13, the power-on button is pushed to energize relay coil R1 and, thereby, to close contacts R1a, R1b, and R1c. Power is now supplied to the machine and, in particular, to light 27a. Light 27a casts a beam 27 of light toward photoelectric cell 27b which reacts by closing contact 27c and transmitting electrical current to relay coil R3. When thus energized, relay coil R3 causes contact R3a to close. This permits relay coil R2 to be energized through now closed contact R3a and normally closed contact TR1a when the machine operator presses push button PB1 to begin the machine sequence.

Energized relay coil R2 causes the closing of normally open contacts R2a, R2b, and R2c; permits the release of PB1, by the operator; and, provides current through now closed contact R2c and normally closed contact R15a for relay coil R4 which enables the closing of contact R4a to which core plugging sub-assembly hopper drive means 40c are connected and the energizing of such drive means for the purpose of beginning a sorting of plugs 40b in barrels 40a.

Once contact R2b is closed, timer relay coil TR1 is energized and closes contact TR1b. Solenoids 17 and 21 are also energized; the energy flowing to solenoid 17 operates a valve therein which causes the retraction of piston 15 into cylinder 16 and the removal of chock 14 from in front of roll A and that flowing to solenoid 21 operates a valve therein which causes the extension of chock 18 on piston 19 from cylinder 20 into the path of roll A upon its release by chock 14. The energy in relay coil TR1 effects the starting of the timer which is connected thereto and is adapted to open normally closed contact TR1a, thereby de-energizing relay coil R2 and opening contacts R2a, R2b, and R2c, but not contact R4a, when a predetermined amount of time has elapsed and allowed roll A to move down ramp 13 and to settle upon and between rollers 10 and 11, perhaps with the aid of chock 18 on extended piston 19. And, at about the same time, the coming-to-rest of roll A on rollers 10 and 11 interrupts light beam 27, causing contact 27c to open, relay coil R3 to be de-energized, and contact R3a to open, so that even an accidental pushing of PB1 by the operator will not cause another unfinished paper roll to come down ramp 13 into collision with roll A.

When contact TR1b is closed energy can flow to the

latching means of latch relay LR1, can close contact LR1a, and can energize relay coil R5. The energizing of relay coil R5, which is connected to drive means 28 for rollers 10 and 11, starts such drive means and causes rollers 10 and 11 and Roll A thereon to rotate. It also contact R5a so as to energize spring-loaded solenoid valve 90 (FIGURE 12), which is in fluid connection with air pipes or hoses designated as arrows D and E in FIGURE 5 and to cause air jets emanating therefrom to blow tail F of roll A into the beam 29 of light 29a. The interruption of the transmission of beam 29 to photoelectric cell 29b closes contact 29c and energizes relay coil R6. When relay coil R6 is energized normally open contacts R6a, R6b R6c are closed.

15 The closing of contact R6a causes current to flow to the unlatching means of latch relay LR1; the closing of contact R6b assures a continued flow of current to drive means 28 at least until tail F no longer interrupts beam 29 and, as a result, contact 29c opens and effects the 20 de-energizing of relay coils R5 and R6 and the solenoid having valve 90; and, the closing of contact R6c causes current to flow to the latching means of latch relay LR2 which is electrically connected to drive means 53 and 73 for lead screws 51 and 71.

25 When latch relay LR2 is thus energized, contact LR2a closes, energizing relay coils R7 and R8 through normally closed contacts 64a and 84a of limit switches 64 and 84. Relay coils R7 and R8 energize drive means 53 and 73 causing trolley carriage members 50 and 70 to approach opposite ends of roll A until physical contact is made between such limit switches and such ends and the switches are thereby opened.

When limit switch contacts 64a and 84a are opened, contacts 64b and 84b are closed, so that current flows to 35 relay coil R9 through normally closed contact LR4a. Energized relay coil R9 closes contacts R9a and R9b and causes current to flow to the unlatch-means of latch relay LR2 (whereupon relay coils R7 and R8 are de-energized to stop drive means 53 and 73) and to drive 40 means 65 and 85 (whereupon elevator carriage members 63 and 83 within trolley carriage members 50 and 70 start to rise on lead screws 62 and 82 connected to such drive means).

During the ascent of elevator carriage members 63 and 83, light 67a casts a beam 67 through hollow core G of roll A to impinge against photoelectric cell 67b, as soon as there is a clear path, and to cause the closing of contact 67c. When contact 67c is closed, the latching means of latch relay LR3 is energized and closes contact LR3a. Now, both contacts R9b and LR3a are closed, permitting the flow of current to the starting means of a timer TR2 which is set to end the ascent of elevator carriage members 63 and 83 when they have travelled the predetermined vertical distance between the line of beam 67 and the center-lines of spindles impaling plugs 40b within members 63 and 83. At such point, plugs 40b are positioned substantially axially of core G of roll A and timer TR2 closes contact TR2a, so as to energize the latching means of latch relay LR4 and open normally closed contact LR4a, which opening shuts off drive means 65 and 85.

60 Further, energized latch relay LR4 closes normally open contact LR4c, thereby energizing spring-loaded solenoid valves 91 and 92 which are connected to cylinders 60 and 80 and solenoid valves 93 and 94 which are connected to cylinders 31 and, by hose line 34a, to glue heads 30. Thereupon cylinders 60 and 80 eject spindles 60a and 80a bearing impaled plugs 40b into the ends of core G of roll A and cylinders 31 eject pistons 31a bearing glue heads 30 while solenoid valves 93 and 94 supply air to glue heads 30. Latch relay LR4 also closes normally open contact LR4b, thereby energizing timer relay TR3 which is adapted to open contact TR3a, de-energized solenoid valves 91 and 92 at the end of a predetermined period marked by the withdrawal of spindles 60a and 80a from core-lodged plugs 40b, and close contact TR3b. On the

other hand, solenoid valves 93 and 94 are de-energized when feeler 35 strikes switch 36.

When contact TR3b closes, relay coils R10 and R11 are energized and, through them, drive means 53 and 73 for lead screws 51 and 71. Relay coils R10 and R11 are subsequently de-energized when trolley carriage members 50 and 70 move apart sufficiently to impinge at their rear ends against limit switch contacts 54a and 74a. When this occurs, limit switch contacts 54b and 74b are closed and relay coils R12 and R13 are fed current. With the flow of current through relays R12 and R13, reversible elevator carriage member drive means 65 and 85 are started and carriage members 63 and 83 begin to descend. Contact R12b is, in turn, closed and allows current to flow to the valve of solenoid 25 which causes the ejection of piston 23 from cylinder 24 and, thereby, the nudging of roll A off of rollers 10 and 11 by prod roller 22. Such descent is ended when carriage members 63 and 83 come down on and open normally closed limit switch contacts 69a and 89a to de-energize relays R12 and R13. When limit switch contacts 69a and 89a are opened, limit switch contacts 69b and 89b are closed and this makes current flow to relay R14 and timer TR4.

Energy in relay R14 closes contact R14a and energizes solenoid valves 95 and 96 connected to cylinders 55 and 75. Energized solenoid valves 95 and 96 cause the ejection of pistons 56 and 76 from cylinders 55 and 75 and, by means of levers 57 and 77 and pivot shafts 58 and 78, the swinging of cylinders 60 and 80 through arcs of about 90° to positions axially of oriented plugs 40b in hopper pick-up stations 40j.

The swinging of cylinders 60 and 80 through arcs of about 90° causes them or spindles 60a and 80a to impinge against limit switches 68 (FIGURE 8) and 83 (in like positions on elevator carriage member 83). Such limit switches are thereby closed, so as to energize relay coil R15 and open normally closed contact R15a. The opening of such contact stops hopper drive means 40c thereto. Energy in relay R15 also energizes solenoid valves 91 and 92 to extend spindles 60a and 80a from cylinders 60 and 80, so as to impale oriented plugs 40b in pick-up stations 40j.

At this juncture, energized timer TR4 is adapted to open normally closed contacts TR4a and TR4b, thereby de-energizing relays R14 and R15. When relay R15 is de-energized, spindles 60a and 80a retreat into cylinders 60 and 80, taking along impaled plugs 40b. When relay R14 is de-energized, cylinders 60 and 80 swing back through arcs of about 90° to positions generally parallel to rollers 10 and 11, because of the retraction of pistons 56 and 76 into cylinders 55 and 75.

The machine is now at the end of its full, preferred cycle of operation and in a neutral condition, awaiting the operator's pushing of push-button PB1.

What is claimed is:

1. In a machine for finishing a roll of a web wound about a hollow core, in combination, a roll feed means responsive to gravity, a roll chocking means, a roll positioning means, a roll position sensing means, a roll chocking release means responsive to the roll position sensing means, a roll tail gluing sub-assembly responsive to the roll position sensing means, and two core plugging sub-assemblies responsive to the roll position sensing means wherein the roll tail gluing sub-assembly comprises a roll rotating means, a roll tail positioning means, and a glue application means and the core-plugging sub-assemblies comprise core plug orienting means, core plug pick-up means, core plug travelling means, and core plug inserting means.

2. The machine of claim 1 in which the roll positioning means are a pair of horizontally disposed, spaced-apart rollers.

3. The machine of claim 1 in which the roll positioning means and the roll rotating means are connected.

4. The machine of claim 1 in which the roll tail positioning means include air jet means.

5. The machine of claim 1 in which the roll tail positioning means include air jet means and roll rotating cut-off means.

6. The machine of claim 5 in which the air jet means are directed to move the tail and the roll rotating cut-off means are responsive to the movement of the tail.

7. The machine of claim 6 in which the roll rotating cut-off means include photo-electric elements.

8. The machine of claim 1 in which the glue application means are mounted on the core-plugging sub-assemblies.

9. The machine of claim 1 in which the core plug orienting means include horizontally disposed, rotatable barrels provided at an end with a plurality of aperture defining means.

10. The machine of claim 9 in which the aperture defining means substantially conform to the core plug profiles.

11. The machine of claim 1 in which the core plug orienting means include a vertically disposed neck, means defining a core plug receiving opening at the upper end of the neck, and means defining a core plug discharging opening at the lower end of the neck.

12. The machine of claim 1 in which the core plug orienting means include a vertically disposed neck, means defining a core plug receiving opening at the upper end of the neck, means defining a check to store oriented plugs adjacent the core plug receiving opening, and means defining a core plug discharging opening at the lower end of the neck.

13. The machine of claim 1 in which the core pick-up means include core plug impaling means.

14. The machine of claim 1 in which the core plug orienting means include a vertically disposed neck, means defining a core plug receiving opening at the upper end of the neck, and means defining a core plug discharging openings at the lower end of the neck and the core pick-up means include core plug impaling means and in which the core plug impaling means are operable to withdrawn core plugs from the core plug discharging openings.

15. The machine of claim 1 in which the core plug travelling means include trolley carriage members and elevator carriage members.

16. The machine of claim 15 in which the trolley carriage members are movably disposed at opposite ends of the roll and the elevator carriage members are movably disposed with the trolley carriage members.

17. The machine of claim 1 in which the core plug inserting means include elevator carriage member vertical drive means, hollow core detecting means, and elevator carriage member vertical drive cut-off means.

18. The machine of claim 17 in which the elevator carriage member vertical drive means are responsive to the hollow core detecting means.

19. The machine of claim 18 in which the hollow core detecting means include photo-electric elements.

20. The machine of claim 16 in which the glue application means are mounted on the trolley carriage members and the core plug inserting means include elevator carriage member vertical drive means and in which the glue application means and the elevator carriage member drive means are responsive to contacts between the trolley carriage members and the opposite ends of the roll.
